BICYCLE STAND

Daniel C. Myers, Arvada, Colo., assignor to
Daka Industries, Inc.

Filed July 5, 1973, Ser. No. 376,630

Term of patent 14 years

Int. Cl. D8—99

U.S. Cl. D12—115

FIG. 4

FIG. 6

FIG. 5

FIG. 7

FIG. 11

FIG. 13

FIG. 12

FIG. 14

FIG. 1 is a side elevational view of a bicycle stand embodying my new design.

FIG. 2 is a top plan view thereof.

FIG. 3 is a perspective view of one segment of the bicycle stand shown in FIG. 1.

FIG. 4 is a front elevational view of the segment shown in FIG. 3.

FIG. 5 is a rear elevational view of the segment shown in FIG. 3.

FIG. 6 is a right side elevational view of the segment shown in FIG. 3.

FIG. 7 is a left side elevational view of the segment shown in FIG. 3.

FIG. 8 is a side elevational view of a bicycle stand showing a second embodiment of my new design.

FIG. 9 is a top plan view thereof.

FIG. 10 is a perspective view of one segment of the bicycle stand shown in FIG. 8.

FIG. 11 is a front elevational view of the segment shown in FIG. 10.

FIG. 12 is a rear elevational view of the segment shown in FIG. 10.

FIG. 13 is a right side elevational view of the segment shown in FIG. 10.

FIG. 14 is a left side elevational view of the segment shown in FIG. 10.

I claim:

The ornamental design for a bicycle stand, as shown.
